UNITED STATES PATENT OFFICE.

EDWARD JOHNSON, OF SEATTLE, WASHINGTON.

WINDOW SAFETY APPLIANCE.

Application filed August 21, 1924. Serial No. 733,426.

To all whom it may concern:

Be it known that EDWARD JOHNSON, a citizen of the United States, residing at Seattle, in the county of King and State of Washington, has invented certain new and useful Improvements in Window Safety Appliances, of which the following is a specification.

This invention relates to a guard, designed particularly for use to protect window cleaners against falling when standing on the sills to clean the outer surfaces of the window.

The invention comprehends a frame structure which is laterally adjustable to accommodate windows of different widths, and which is adapted to be clamped against the inner and outer surfaces of the wall adjacent the window frame, when in use with single windows, and which is also adapted to be clamped with relation to the stiles, or with the stiles on one side and the wall on the other, where the device is used with double or triple windows.

The invention is illustrated in the accompanying drawings, in which:—

Figure 1 is a view in side elevation of the improved guard.

Figure 2 is a front elevation of the same.

Figure 3 is a plan showing the same in use with a single window.

Figure 4 is a transverse section through the guard.

Figure 5 is a broken plan showing the guard in use with a double window.

Figure 6 is a similar view, showing the guard in use with a triple window.

Figure 7 is a view in elevation showing the application of the auxiliary abutment to the main abutment as is desired in the use of the guard with double or triple windows.

The guard, which is preferably constructed of metallic rods of suitable size and strength is made up in two duplicate sections, adapted for adjustable interconnection to vary the width of the guard at will, and as required. Each section includes an upright 1, of appropriate height, with a lateral extension 2 at the upper end, terminating in an eye 3. The lower end of the upright 1 is bent into U-form at 4 and then projected forwardly at 5, with the terminal of the portion 5 threaded to receive a turn buckle 6.

The forward portion of each section includes a length 7 terminally threaded to re-

ceive the turn buckle 6, the forward end of length 7 being formed into a laterally projected loop 8 and then extended laterally at 9 with a terminal eye 10. The respective sections, one of which has been described, and which are in duplicate, are connected by having the respective eyes 3 and 10 of each section slidably receive lateral portions 2 and 9 of the other section, so that the sections are thus slidably connected together, and may obviously be adjusted to any desired width within the limits of the sections.

If desired and as preferred the lower portions of the upright 1 may be connected by brace bars 11, each terminating in an eye 12 to slidably embrace the other bar 11, thus affording a brace at the lower ends of the upright without interfering with the adjustability of the structure.

The U-portions 4 at the lower ends of the upright 1 are bridged by plates 13, having marginal portions 14 which are coiled about the respective branches of the U-portion, and if desired the brace bars 11 may be anchored in these plates. The upper margins of the plates are formed to provide sleeve bearings 15 in which are rotatably supported the intermediate length 16 of what will be termed the abutment lever 17. This lever has a forward length 18 and a rear length 19, both of which are arranged at right angles to the intermediate length 16, and also at right angles to each other. Thus either length 18 or 19 may be turned into a position at right angles to the section 5, in which position such length forms the outer abutment for the clamp of the guard. As the lengths 18 and 19 are spaced apart by the intermediate length 16, this adaptability of the abutment lever obviously provides an adjustment in the position of the outer clamp abutment, as is advisable in accommodating walls of different thicknesses.

The inner abutment is formed by a block 20 centrally channeled at 21 to cooperate with the loop 8 of each section, this inner main abutment presenting a broad bearing surface 22 to engage the inner wall surface, as will later appear. The upper end of the main abutment 20 is reduced at 23 to receive an auxiliary abutment shown more particularly in Figures 5, 6 and 7. This auxiliary abutment comprises a metal loop 24 formed to more or less accurately fit the reduced

portion 23 of the main abutment, the auxiliary abutment terminating in an appropriately formed foot 25 connected with a loop by bar 26. If desired the auxiliary abutment, which is readily removable from the main abutment when desired, may be made of a metallic strip, appropriately bent, as indicated in Figures 5 and 6 to form such abutment.

10 The terminal of the forward length 18 of the abutment lever 17 is provided with angle strip 27 having a right angle terminal 28, this angle strip forming an extension of the abutment lever for wall engaging purposes, as will be evident.

In use of the guard with single windows, as illustrated in Figure 3, the guard extensions are moved laterally to the width permitted by the window, the inner abutments 20, with the auxiliary abutments removed, are brought to bear against the inner surface of the wall immediately beyond the window frames. The angle levers 17 are adjusted to provide outer abutments to engage the outer surface of the wall beyond the window frame, and the turn buckles 6 are tightened to cause the clamping cooperation of said abutments with the wall necessary to fix the guard in position. The upper rights 1 and lateral bars 2 are thus disposed beyond the window sill and of sufficient height to prevent the window cleaner from falling outwardly.

In the use of the guard with double or triple windows, the operation is the same except that where the guard is designed to engage the stile between the windows, the auxiliary abutment 24 is applied to the upper end of the main abutment, to permit the formed end 25 of the auxiliary abutment to bear against the window stile. In use

with the intermediate window of the three window frame, both main abutments are provided with auxiliary abutments, as indicated in Figure 6.

45

What I claim is:—

1. A window guard comprising an outer upstanding frame, including side bars and adjustable end bars, an inner sill engaging frame comprising relatively adjustable connected bars, abutment members movably supported at the ends of each of the bars of the inner sill engaging frame, the side bars being connected to the inner frame bars inwardly of the abutments and being adjustable to vary the positions of the outer and inner frames relative to each other, the abutments being located wholly beyond the side bars, and levers movably mounted at the juncture of the side bars and outer frame and adapted to be turned into position to engage the outside of the window frame.

50

2. A window guard comprising an outer upstanding frame, including side bars and adjustable end bars, an inner sill engaging frame comprising relatively adjustable connected bars, abutment members movably supported at the ends of each of the bars of the inner sill engaging frame, the side bars being connected to the inner frame bars inwardly of the abutments and being adjustable to vary the positions of the outer and inner frames relative to each other, the abutments being located wholly beyond the side bars, and auxiliary abutments adapted to engage the first mentioned abutments in the use of the guard with double windows to thereby extend the abutments to engage the stile between the windows.

55

In testimony whereof I affix my signature.
EDWARD JOHNSON.
